To all whom it may concern:

Be it known that I, Richard B. Janes, a citizen of the United States, residing at Detroit, in the county of Wayne and State of Michigan, have invented a new, original, and ornamental Design for a Refrigerator Cabinet, of which the following is a specification, reference being had to the accompanying drawing, forming a part thereof.

In the drawing—

Figure 1 is a front perspective view of the refrigerator cabinet, embodying my new design;

Figure 2 is a side elevational view of the refrigerator cabinet shown in Figure 1;

Figure 3 is a top plan view of the refrigerator cabinet shown in Figures 1 and 2; and

Figure 4 is an enlarged top plan view of the handle area of the refrigerator cabinet, partly in section, taken along the line 4—4 of Figure 1.

The characteristic feature of my design resides in the combination on the refrigerator cabinet disclosed of the depressed door formation in association with the handle, all as shown.

I claim:
